ABSTRACT OF THE DISCLOSURE

A drafting frame for fibrous material having a series of nipped pairs of drafting rolls which are driven at progressively higher speeds with a single centrally located backup roll being provided for each of the slower speed drafting rolls and with a pair of arcuately spaced backup rolls being provided for each of the higher speed drafting rolls.

This is a continuation of my copending application Ser. No. 621,608, filed Mar. 8, 1967, now abandoned.

BACKGROUND OF THE INVENTION

The invention relates to drafting frames having pairs of fluted nipped drafting rolls between which a series of slivers of fibrous material may be passed. In drafting equipment of this type, pairs of aligned top and bottom fluted drafting rolls are held together in nipped engagement under predetermined amounts of pressure as the fibrous material passes between them, and these rolls are driven by gearing at progressively faster speed so that the slivers of fibrous material are laterally spread out into the form of a thin web and so that, at the same time, the fibrous material passing between the rolls is stretched or drafted to more perfectly align the fibers longitudinally of the thin web.

In equipment of this type, the lengths of the drafting rolls determines the width of the thin fibrous web that may be formed by the drafting rolls. The drafting rolls, depending on the type of fibrous material utilized, are quite small in diameter, such as on the order of two inches, for example; and as the width of the web desired and the length of the drafting rolls are increased, the drafting rolls become relatively flexible so that the nip pressure between the drafting rolls undesirably varies from end to end of each pair of drafting rolls. The distances between the flutes in the drafting rolls peripherally of the rolls, therefore, the diameters of the drafting rolls, as well as the distances between the pairs of drafting rolls, are dependent on the length of the individual fibers in the fibrous material; and, therefore, at least for some types of fibrous material, it is not possible to increase these dimensions while yet securing the desired stretching or drafting of the fibrous material and the desired lateral spreading action which causes individual slivers being fed into the drawing apparatus to be spread out into a relatively uniform thin web of fibrous material. It is thus not possible to overcome such flexing of long drafting rolls simply by increasing the diameters of the drafting rolls.

There is a different problem with respect to the relatively slow rotating drafting rolls, which are the rolls acting first on the slivers, than there is with respect to the faster rotating drafting rolls, which are the last rolls in the drafting frame acting on the fibers. There is quite a heavy thickness of sliver passing between the slow rotating drafting rolls; and, therefore, the principal problem is simply a static flexing problem, with the slow rotating rolls being forced apart by the relatively thick slivers.

The thickness of sliver between the relatively fast drafting rolls is considerably reduced, since each pair of draft-

2

ing rolls reduces the thickness of the slivers and laterally spreads the slivers into a more uniform web. There, therefore, is no great static force tending to move the fast rotating drafting rolls apart, but these drafting rolls rather tend to oscillate, flex and whip due to dynamic forces. In a wide drafting frame, each of these fast rotating rolls, being long and limber, has a critical speed at which it tends to whip; and assuming that substantial production is desired from the apparatus, this critical speed is approached with the fast rotating drafting rolls. The nip loading between these fast rotating drafting rolls is very, very slight, due to the small amount of fiber between these rolls, but since the speeds of these rolls may be very high, these rolls whip, particularly in their center regions, and thereby produce a fibrous web that is non-uniform and therefore unsatisfactory.

SUMMARY OF THE INVENTION

It is an object of the present invention to provide an improved drafting frame of this type which is of such construction that the fluted drafting rolls may be maintained under substantially uniform nip pressures from end to end and in which the dynamic forces tending to cause the faster rotating of these rolls to whip are counter balanced, even though the drafting rolls are relatively long and small in diameter.

In a preferred form of the apparatus, the deflection forces on each slower moving drafting roll is counter balanced by a supporting roller placed centrally along the length of the roll, with the two support rollers for the drafting rolls of each pair being disposed in a plane passing through the centers of the two drafting rolls of the pair. The dynamic whipping forces, with respect to the faster moving drafting rolls, are also balanced by support rollers centrally located along the length of each of the faster rotating rolls; however, each of the faster moving rolls is provided with a plurality of such support rollers, and these support rollers are arcuately spaced about the periphery of each of these drafting rolls. Assuming that two support rollers for each of the faster drafting rolls are used, these support rollers may be placed, for example, at 10 o'clock and 2 o'clock with respect to the upper one of a pair of the fast rotating rolls, and the support rollers for the bottom one of the pair may be placed at 4 o'clock and 8 o'clock, these positions being located with respect to a plane passing through the centers of the upper and lower fast rotating drafting rolls.

The invention consists of a novel construction to be hereinafter described and claimed for carrying out the above stated objects, and such other objects, as will be apparent from the following description of a preferred form of the invention, illustrated with reference to the accompanying drawings.

BRIEF DESCRIPTION OF THE DRAWINGS

FIG. 1 is a perspective view of a drafting frame together with gearing for driving the fluted drafting rolls of the apparatus without showings (for better illustration of the basic drafting frame) of the support rollers for the drafting rolls constituting an important feature of the invention;

FIG. 2 is a sectional view of the two fluted drafting rolls and taken from line 2—2 of FIG. 1;

FIG. 3 is a side elevational view of a certain drive gearing of the apparatus and taken from line 3—3 of FIG. 1;

FIG. 4 is a sectional view showing certain other gearing of the apparatus and taken from line 4—4 of FIG. 1;

FIG. 5 is a top plan view of the gearing shown in FIG. 4 and taken from line 5—5 of FIG. 4;

FIG. 6 is a fragmentary top plan view of the fluted drafting rolls of the apparatus and showing support rollers for each of the top drafting rolls;

FIG. 7 is a sectional view taken on line 7—7 of FIG. 6;

FIG. 8 is a fragmentary elevational view of one of the top drafting rolls and a pair of support rollers for the drafting roll and taken from line 8—8 of FIG. 7; and

FIG. 9 is a sectional view taken on line 9—9 of FIG. 8.

Like reference characters designate like parts in the several views.

DESCRIPTION OF THE PREFERRED EMBODIMENT

Referring now to the drawings and in particular to FIGS. 1 and 7, the illustrated drafting apparatus may be seen to comprise upper drafting rolls 10, 11, 12, 13 and 14 and lower drafting rolls 15, 16, 17, 18 and 19. The roll 15 is disposed directly below the roll 10 and has a nip with the roll 10 so as to form a pair of cooperating drafting rolls, and the same is true with respect to the rolls 11 and 16, the rolls 12 and 17, the rolls 13 and 18, and the rolls 14 and 19, respectively. The rolls 10 to 14 rotate progressively at greater speeds, and the lower rolls 15 to 19 each rotates at the same speed as the upper roll with which the lower roll has a nip. Each of the rolls 10 to 19 is longitudinally fluted and the pairs of rolls have their flutes intermeshing; and preferably the faster rotating ones of the rolls 10 to 19 are provided with a greater number of finer flutes than the slower rotating rolls. The rolls 10 to 19 are mounted in a frame 20 in any suitable manner, such as, for example, in the manner indicated in U.S. Pat. 3,203,051 issued on Aug. 31, 1965, to J. R. Whitehurst.

The lower rolls 15 to 19 are driven at progressively higher speeds, and this may be accomplished by means of any suitable gearing, such as, for example, the gearing that is illustrated in FIGS. 1, 3, 4 and 5. Each of the upper rolls 10 to 14 rotates along with the lower roll with which it forms a pair due to the intermeshing relationship of the upper roll to the lower roll of the pair, and the upper and lower rolls of each pair are held in nipped relationship by means of suitable mechanism associated with the frame 20. This nipped relationship is preferably such that there is a slight clearance between the top and bottom rolls of each pair when no fibers are passed through the drafting apparatus.

The roll 19 is the fastest rotating lower roll, and this roll has a spur gear 21 fixed to it which is in mesh with a larger gear 22 mounted on a countershaft 23. A gear 24 is fixed to the gear 22 and meshes with a larger gear 25 which is fixed with respect to the intermediate lower drafting roll 17. The gear 21 is driven from any suitable prime mover (not shown), and the roll 17 is driven in the same direction of rotation but at a slower speed by means of the gear train 21, 22, 24 and 25 due to sizes of these gears.

The gear train 21, 22, 24, 25 is located on one side of the frame 20; and gearing for driving rolls 15, 16 and 18 is located on the other side of the frame 20. The latter gearing comprises gears 26, 27, 28, 29 and 30 which are respectively fixed on the rolls 19, 18, 17, 16 and 15. The gears 26, 28 and 30 are located in line close to the frame 20; and the gears 27 and 29 are located in line but out of line with gears 26, 28 and 30 and more remote from the frame 20. A pair of gears 31 and 32 are fixed together and are disposed on a countershaft 33 with the gear 31 in mesh with the gear 26 and the gear 32 in mesh with the gear 27. The gear 26 is smaller than the gear 31 and the gear 32 is smaller than the gear 27; and, therefore, the drafting roll 18 is driven from the drafting roll 19 in the same direction but at a slower speed.

A pair of gears 34 and 35 are fixed together and are rotatably disposed on a countershaft 36. The gear 34 is in mesh with the gear 28 and the gear 35 is in mesh with the gear 29; and, since the gear 28 is smaller than the gear 34 and since the gear 35 is smaller than the gear 29, the drafting roll 16 is driven from the drafting roll 17 at a slower speed than the roll 17.

A pair of gears 37 and 38 are fixed together and are rotatably disposed on a countershaft 39. The gear 37 is in

mesh with the gear 29, and the gear 38 is in mesh with the gear 30; and, particularly since the gear 37 is larger than the gear 29, the drafting roll 15 is driven in the same direction as and at a slower speed than the drafting roll 16.

The rolls 10 and 15, which are the slowest rotating fluted drafting rolls in the apparatus, are respectively supported by rollers 40 and 41 (see FIGS. 6 and 7). The centers of the rolls 10 and 15 are in a vertical plane 42, and the centers of the support rollers 40 and 41 are likewise in this plane. The support rollers 40 and 41 are located approximately in the center of the rolls 10 and 15, that is, midway between the ends of the rolls 10 and 15. The successively faster moving roll pairs 11, 16 and 12, 17 are supported centrally of their ends in the same manner as the rolls 10 and 15, the rolls 11 and 16 being respectively supported by support rollers 43 and 44 and the rolls 12 and 17 being respectively supported by support rollers 45 and 46.

The lower drafting roll 18 of the roll pair 13, 18 is supported by means of rollers 47 and 48, and the upper roll 13 of this pair is supported by rollers 49 and 50. The planes of the support rollers 47 and 48 are out of alignment with respect to each other but both of the rollers 47 and 48 are disposed approximately midway between the ends of the drafting roll 18; and the support rollers 49 and 50 for the upper drafting roll 13 are arranged in the same manner with respect to each other and with respect to the drafting roll 13. The centers of the rollers 47, 48, 49 and 50 are disposed on opposite sides of a plane 51 passing through the respective centers 52 and 53 of the drafting rolls 13 and 18, the rollers 47 and 48 being respectively positioned approximately at the 8 o'clock and 4 o'clock positions with respect to the center 53 of the roll 18, and the rollers 49 and 50 being positioned approximately at the 10 o'clock and 2 o'clock positions with respect to the center 52 of the roll 13. Each of the support rollers 47 and 48 thus provides a component force tending to hold the roll 18 against movement along a plane perpendicular to the plane 51, and the same is true of the support rollers 49 and 50 with respect to the drafting roll 13.

The fastest rotating drafting rolls 14 and 19 of the drafting installation are supported in the same manner as are the rolls 13 and 18, by means of support rollers 54 and 55 for the lower roll 19 and by means of rollers 56 and 57 for the roll 14 (see FIGS. 6, 7, 8 and 9). The rolls 54 and 55 are disposed at the 8 o'clock and 4 o'clock positions with respect to the roll 19, and the rolls 56 and 57 are disposed at the 10 o'clock and 2 o'clock positions with respect to the roll 14.

It is desirable that the upper rolls 10, 11, 12, 13 and 14 be removed at times from the drafting apparatus, such as for example, to relieve plug-ups of sliver passing between the drafting rolls; and, therefore, the rollers 40, 43, 45, 49, 50, 56 and 57 are mounted so that they may be elevated to allow the upper drafting rolls 10 to 14 to be removed. In this connection, it may be mentioned that the upper drafting rolls 10 to 14 each preferably is rotatably mounted in open grooves provided in the frame 20, such as for example, as shown in U.S. Pat. 3,203,051 previously mentioned to allow the upper rolls to be removed from the frame 20. In order to illustrate the manner in which the rollers 40, 43, 45, 49, 50, 56 and 57 may be mounted, FIGS. 8 and 9 may be referred to showing the mounting apparatus for the rollers 56 and 57. The rollers 56 and 57 are carried by a cage assembly 58 which is rotatably disposed about a shaft 59 that is fixed at its opposite ends in the frame 20. An air cylinder 60 is connected to the assembly 58 and is suitably supported with respect to the frame 20 so that the assembly 58 and rollers 56 and 57 may be held in their positions illustrated in FIGS. 8 and 9 and the rollers 56 and 57 may be swung upwardly along with the assembly 58 so as to allow the drafting roll 14 to be removed from the drafting frame.

The lower rolls 41, 44, 46, 47, 48, 54 and 55 may be

mounted with respect to the frame 20 in the same manner as the upper rollers except that there is generally no need to move the lower rollers out of their operative positions supporting the respective rolls 15 to 19; and, therefore, roller holder assemblies corresponding to the assembly 58 need have no air cylinder releasably holding them in position and instead rigid support bars may be provided for holding the roller supporting assemblies in operative position.

In operation, the fastest rotating or final drafting rolls 14 and 19 of the drafting apparatus may be driven at, for example, 1360 r.p.m. The roll pairs prior to the pair 14, 19 are successively driven at slower speeds, and the slowest rotating rolls 10 and 15, which are the first rolls in the series of drafting rolls of the apparatus, may, for example, be driven at $\frac{1}{30}$ of the speed of the rolls 14 and 19. Slivers 58 of fibrous material, such as for example, fibers of rayon or nylon, are drawn into the drafting apparatus between the rolls 10 and 15; and there may, for example, be two to four slivers per inch of length of the rolls 10 and 15. The slivers are compressed between the rolls 10 and 15, and these rolls 10 and 15 thus have a force from the slivers tending to force the rolls 10 and 15 apart. The fibrous material thereafter passes successively between the rolls 11, 16, 12, 17, 13, 18 and 14, 19, and each successive pair of these rolls rotate faster than the preceding pair so that the fibrous material is drafted or stretched and individual fibers are drawn more closely into the longitudinal direction of movement. At the same time, the fibers move laterally and spread so that, as the fibrous material passes out from between the rolls 14 and 19, there is a substantially uniform web.

The maximum desirable diameters of the drafting rolls 10 to 19 and also the maximum desirable spacing between the pairs of these drafting rolls are dependent on the length of fibers in the fibrous material to be drafted, if the proper drafting effect is to be attained. The fibers of the fibrous material may be, for example, about $2\frac{1}{4}$ inches in length; and, in this case, the diameters of the drafting rolls should preferably be no more than $2\frac{1}{4}$ inches and the spacing between the drafting roll pairs should preferably be no more than $2\frac{1}{2}$ inches. Using these dimensions, there thus is only a slight clearance between successive pairs of the drafting rolls. If relatively long drafting rolls 10 to 19 are used, for example, 60 inches in length, in lieu of 15 or 20 inch length rolls conventionally used, the drafting rolls, if of a $2\frac{1}{4}$ inch diameter, become unduly flexible and limber, particularly when they are made in lengths greater than about 40 inches; and this is true even though high quality steel is used in the manufacture of the drafting rolls. Since the fiber length more or less dictates the diameter of the drafting rolls and of the spacing between the drafting roll pairs, it is not possible to remedy this condition of undue flexibility by increasing the diameters of the drafting rolls. Therefore, according to the present invention, the supporting rollers 41 to 45 and 48 to 56 have been provided for supporting the drafting rolls 10 to 29 to overcome the effects of the undue flexibility of the drafting rolls, which effects are primarily encountered with rolls having a relatively high ratio of length to diameter, such as at least 20 to 1, based on the above stated dimensions of 40 inch roll length between lateral supports and $2\frac{1}{4}$ inch roll diameter.

The slower rotating drafting rolls 10, 11, 12, 15, 16 and 17, all of which rotate at speeds less than a predetermined speed, do not have relatively great dynamic stresses tending to move them out of a uniform nipped relationship in the roll pairs; however, the slivers 58 passing between these slower rotating rolls have appreciable thickness, and these rolls therefore tend to deflect or bow outwardly with respect to each other under the static forces due to the slivers 58. These rolls have, therefore, been braced by the support rollers 41, 42, 43, 44, 45 and 46 which lie directly in the planes in which the centers of

the drafting rolls are disposed, for example, in the plane 42 of the centers of the rolls 10 and 15. These centrally disposed supporting rollers 40 and 41 thus take the deflection forces and maintain substantially uniform nips between these pairs of rolls.

The forces on the other higher speed drafting rolls 13, 14, 18 and 19 tending to move them out of perfectly straight condition are primarily dynamic due to the high-speeds of rotation. The thickness of sliver between these fast moving rolls is considerably reduced, and there is no appreciable force tending to bow the drafting frame rolls apart, but these fast rotating drafting rolls rather tend to oscillate, flex and whip due to their high speeds; and, even though these high speed drafting rolls are practically perfectly balanced, they still have a critical speed at which they tend to whip. At this critical speed, there is a resonant condition which is dependent on the modulus of elasticity of the material from which the drafting rolls are made, the length of the drafting rolls between supports, the speed of the rolls and the roll diameters. This critical speed is approached at the speeds contemplated for these high speed rolls; and any such whipping action, of course, will change the thickness of the nips between these high speed roll pairs and will produce a fibrous product that is non-uniform and therefore unsatisfactory.

The supporting rollers 47, 48, 49, 50, 54, 55, 56 and 57, which are arcuately spaced about the particular drafting rolls that the rollers support, such as at the 10 o'clock, 2 o'clock, 4 o'clock and 8 o'clock positions previously described, have the effect of preventing this whipping motion of the high speed drafting rolls due to the fact that these rollers exert a restraining force on the high speed drafting rolls in the direction in which the web moves, that is, perpendicular to the planes, such as the planes 42 and 51, passing through the centers of the pairs of drafting rolls. With respect to either pair of high speed drafting rolls, the rolls 13 and 18 or the rolls 14 and 19, it will be observed that the supporting rollers are disposed not only to each side of the drafting rolls but are also disposed above and below the drafting rolls so that whipping action in any direction, upwardly and downwardly or else in the direction in which the web moves, is thereby prevented.

It will be observed that I have provided drafting roll supporting rollers in positions which are commensurate with the stresses that the particular drafting rolls have on them. The slow speed rolls 10, 11, 12, 15, 16 and 17 have forces which are more or less static and are in the plane containing the centers of the drafting rolls, being due to the slivers passing between the rolls and tending to force them apart. I have, therefore, provided the supporting rollers 41 to 46 which are located in these planes in which the forces occur, and which thus, with a minimum of material, take the particular forces that are effective on these particular drafting rolls. With respect to the high speed drafting rolls 13, 14, 18 and 19, in which the forces are dynamic, tending to cause whipping in all directions, I have braced the drafting rolls from all sides around the quadrant, namely at the 10 o'clock, 2 o'clock, 4 o'clock and 8 o'clock positions previously described. The particular supports, therefore, that I have provided are thus commensurate with the particular forces that are effective on the drafting rolls tending to disrupt a uniform nip between them.

I wish it to be understood that the invention is not to be limited to the specific constructions, arrangements and devices shown and described, except only insofar as the claims may be so limited, as it will be understood to those skilled in the art that changes may be made without departing from the principles of the invention. I also wish it to be understood that the above abstracts of the disclosure shall not be used for interpreting the claims or in any way to limit their scope.

I claim as my invention:

1. Apparatus for drafting fibrous material comprising

a frame, a plurality of fluted drafting rolls rotatably supported at laterally spaced points within said frame, the ratio of the length of each of the drafting rolls between said points relative to its diameter being greater than about 20 to 1, said drafting rolls being arranged in a series of spaced pairs including a first roll pair and a final roll pair with the drafting rolls of each pair having a nip between them and the drafting roll pairs being so arranged that the fibrous material may pass successively between the roll pairs in the series, means for driving said drafting rolls such that successive drafting roll pairs in the series are driven at successively higher speeds with respect to the speed of said first roll pair and said final roll pair is driven at such speed that the rolls tend to whip and deflect in a plane substantially parallel to the passage of the material, a supporting roller means positioned medially of the ends of each drafting roll of said first roll pair for exerting a restraining force thereon to minimize deflections thereof in a plane passing substantially through the centers of both of the drafting rolls of said first roll pair and separation of the drafting rolls of said first roll pair due to the passage of fibrous material therebetween, and a pair of rollers for supporting each of the drafting rolls of said final roll pair positioned medially of the ends thereof and having their centers on opposite sides of a plane passing through the centers of both of the drafting rolls of said final roll pair for exerting a restraining force thereon to minimize deflections thereof in a plane substantially parallel to the passage of the material and for absorbing whipping stresses in the drafting rolls of said final roll pair.

2. Apparatus according to claim 1 for drafting fibrous

material in which said supporting roller means positioned medially of the ends of each drafting roll of said first roll pair comprises a supporting roller having its center substantially in a plane passing through the centers of both of the drafting rolls of said first roll pair.

5 3. Apparatus according to claim 1 for drafting fibrous material in which said series of spaced pairs of drafting rolls includes a first roll pair, a final roll pair, and an intermediate roll pair prior to said final roll pair, and further having a pair of rollers for supporting each of and for absorbing whipping stresses in the drafting rolls of said intermediate roll pair.

10 4. Apparatus according to claim 3 for drafting fibrous material in which adjacent supporting rollers for said intermediate and final roll pairs are staggered to avoid interference therebetween.
